UNITED STATES PATENT OFFICE.

CHARLES BELMONT SEGNER, OF SHIPPENSBURG, PENNSYLVANIA, ASSIGNEE TO
DOMESTIC ENGINE AND PUMP COMPANY, OF SHIPPENSBURG, PENNSYLVANIA, A
CORPORATION OF PENNSYLVANIA.

AIR COMPRESSOR.

Application filed May 18, 1923. Serial No. 561,982.

To all whom it may concern:

Be it known that I, CHARLES B. SEGNER, a citizen of the United States, and a resident of Shippensburg, in the county of Cumberland and State of Pennsylvania, have invented a new and Improved Air Compressor, of which the following is a full, clear, and exact description.

This invention relates to improvements in air compressors, an object of the invention being to provide an air pump with a pair of engine cylinders for operating the pump, the piston rods of the engine and the plunger rod of the pump, being located on a common crank pin with the plunger rod connected to the pin between the pair of piston rods, whereby the full power strokes of the engine pistons are imparted to the crank pin and one power stroke utilized in each complete revolution of the pin.

A further object is to provide an air compressor having an air cylinder positioned at an angle to a pair of internal combustion engine cylinders of the four-cycle type, with the piston rods of the engine cylinders located at opposite sides of the plunger rod of the pump cylinder and connected to the same crank pin whereby a power stroke of each engine piston is utilized upon every complete revolution of the crank shaft.

A further object is to provide an air compressor having an air cylinder and a pair of internal combustion engine cylinders firing alternately and located at an angle to the compressor cylinder with the piston rods of the engine cylinders located at the opposite sides of the plunger rod of the pump cylinder, whereby all compression strokes are power strokes from the respective engines.

A further object is to provide a compressor of the character stated which is constructed to eliminate connecting parts between the engines and the pump plunger and thereby reduce the friction losses and weight, and require but a minimum of space for a machine of given capacity, hence providing a compressor which is compact and which most efficiently performs the functions for which it is intended.

With these and other objects in view, the invention consists in certain novel features of construction and combinations, an ar-

rangement of parts, as will be more fully hereinafter described and pointed out in the claims.

In the accompanying drawings—

Figure 1 is a perspective view taken from one side illustrating my improved compressor as an entirety, mounted upon a suitable vehicle for transportation from place to place.

Figure 2 is a view in elevation of the compressor per se, showing a pair of compressor units coupled together.

Figure 3 is a view of a single compressor unit partly in elevation, but mainly in longitudinal section.

Figure 4 is a view in section on the staggered line 4—4, of Figure 3.

As shown most clearly in Figure 3, my improved apparatus can be complete and efficient in a single compressor unit or, as shown in Figure 2, it may comprise a pair of compressor units, although of course, it is to be understood the invention is not limited to any particular number of units, as I may employ any number desired, all of the compressors being precisely alike the description hereinafter of one, will apply alike to all.

Each compressor unit has a compressor cylinder 1 preferably located in vertical position, as shown most clearly in Figure 4, with a pair of engine cylinders 2, preferably located in horizontal position and at right angles to the compressor cylinder 1. These cylinders 2 form parts of internal combustion engines 3 of the four-cycle type, it being understood that the cylinders are fired alternately.

4 represents a crank shaft mounted to turn in a suitable crank case 5, common to both engine cylinders 3 and compressor cylinder 1 and fly wheels 6 are secured on the crank shaft 4 as shown. 7 represents a crank pin of the shaft 4, and to this crank pin 7 the plunger rod 8 of compressor cylinder 1 is connected and located between the piston rods 9 of the engine cylinders, which are also connected to the same crank pin 7.

10 represents the engine pistons and 11 the compressor plunger, and as above stated, the engines are fired alternately so that by reason of the connection of the engine pis-

2
tons with the same crank pin which operates the compressor, one power stroke is had on the crank pin at each complete revolution of the crank shaft, hence all compression 5 strokes of the plunger 11 of the compressor, constitute power strokes and the maximum of power is imparted to the plunger 11, by reason of the fact that the cylinder 1 is at right angles to the cylinders 2. This power 10 is exerted against the compressor piston during the last half of the compression stroke, which is the period of greatest pressure. The greater amount of power, is therefore, transmitted directly to the compressor without the necessity of being transmitted through a crank shaft and stored in balance 15 wheels and through the medium of couplings and clutches, or other mechanism, as is common with this class of apparatus.

20 While my drawings show the compressor and engine cylinders set at right angles to each other, I do not limit my construction to cylinders at right angles as any other angle may be used that may be desired, the principle remaining the same; viz, connecting two power cylinders, which are parallel and in the same plane, to one compressor cylinder in the same or any other plane, by means of all three connecting rods connected to common crank pin.

30 The crank shaft is preferably provided with balance weights 12 balancing the crank arms to give the best results and assist in reducing the friction and thrust resistance 35 to a minimum.

Within the crank case 5 a cam shaft 13 is located, the cams 14 thereon controlling the valves 15 of engines 3 and said shaft 13 is connected by gears 16 and 17, Fig. 3, with 40 the crank shaft 4.

The compressor cylinder 1 is provided at its upper end with an air inlet cage 18 and an air discharge cage 19 with ring disc valves 20 and 21 respectively, thus controlling 45 communication between said cages and the cylinder 1 and held in normal position by coiled springs 22, so that the movement of the plunger 11 serves to automatically control the positions of the valves and the 50 inlet and discharge of air.

An air inlet manifold 23 communicates with the air cages 18 of the compressor units and an air discharge manifold 24 connects the air discharge cages 19 with an air tank 55 25 in which the air is maintained at any desired pressure.

The engines 3 are water jacketed as shown at 26, which water jackets communicate with a hopper 27 through which air circulating 60 tubes 28 project and the entrance ends of these air circulating tubes 28 communicate with a screened chamber 29 having a fan 30 therein, the shaft 31 of which is provided with a pulley 32 driven by belt 33 from a pulley 34 on crank shaft 4.

The crank case 5 of each compressor unit is provided with a removable plate 35 normally covering an opening 36 which exposes the crank pins and permits access to the connections whenever desired.

In connection with my improved compressor, I provide a complete lubricating system to maintain all of the movable parts properly lubricated at all times and to automatically control such lubrication all of 75 which will now be described.

37 represents a lubricating supply tank or reservoir, and as I preferably use oil, I shall refer to oil as the lubricant.

Oil flows from the tank, or reservoir 37, 80 through a pipe 38 and pipe 39 to sight feed devices 40, 41 and 42. The sight feed device 41 is connected by pipe 44 with the compressor cylinder 1 and supplies lubricant to the latter. The sight feed devices 40 and 42, are connected by pipes 45 and 46 with the engine cylinders 2 and supply lubricant to the latter. The sight feed device 43, is connected to a vertical pipe 47, which directs lubricant through a duct 48 and nozzle 49 into an annular space 50 in an arm, or disc forming part of the crank shaft 4, and from the latter through a central bore 51 and ducts 52 to the crank pin 7 to lubricate the rod connections.

95 Branch pipes 53 and 54 communicate with pipe 47 and convey lubricant to the bearings 55 of crank shaft 4.

A reservoir 56 is located at a low point 100 outside of the crank case and is connected by pipe 57 with an oil strainer 58 in the bottom of the crank case, as is clearly shown in Figures 3 and 4.

An oil pump is located in reservoir 56 105 which pumps the oil in a stream through sight feed device 43 thus flooding the crank shaft and connecting rod bearings, the surplus oil falls to bottom of crank case and flows through oil strainer 58 back into reservoir 56.

110 By this method new oil from reservoir 37 is used for lubricating the engine and compressor cylinders, but as the oil fed to the cylinders is not all consumed the surplus is carried into crank case and thus new oil is being constantly added to the supply in reservoir 56.

115 It is, of course, to be understood that my invention is in no sense limited to the particular manner of lubricating, but I believe 120 the arrangement of lubricating parts is a preferred one, and gives most desirable results.

125 As shown most clearly in Figure 1, my improved compressor may be conveniently mounted on a wheeled vehicle 59, to be moved, or propelled in any desired manner and preferably provided with a frame or housing 60 with movable curtains, or covers 130 61, so that ample protection is afforded the

compressor in bad weather and yet full access may be had to the compressor when in operation.

By thus providing a wheeled vehicle I can conveniently support a gasoline, or other motive fluid supply tank 62 thereon and carry all parts of the apparatus in convenient assemblage.

The operation of my improved compressor is as follows:

Reference being particularly had to a single compressor unit, as the operation of all units are alike, except that where more than one unit is employed the crank throws of the various units may be set at such angles as shall cause the moving parts to be in good balance, and the timing of the engine explosions can be thus regulated for best results.

As the compressor plunger 11 is caused to reciprocate at right angles to a pair of reciprocating power pistons in engines of the four-cycle type, alternately firing, each compressor stroke of the compressor becomes a power stroke, and this is due to the fact that the connecting rods of the pistons and the plunger, are on a common crank pin and the maximum of power is utilized, and because of the fact that the compressor cylinder is at right angles to the engine cylinders the full power stroke of each engine piston gives a direct full power stroke or compression stroke, to the compressor plunger.

Various slight changes might be made in the general form and arrangement of parts

described without departing from my invention, and hence I do not limit myself to the precise details set forth, but consider myself at liberty to make such changes and alterations as fairly fall within the spirit and scope of the appended claims.

I claim:

1. An air compressor comprising a single pump cylinder, a pair of cylinders of an internal combustion engine of the four-cycle type alternately firing, pistons in the pump and engine cylinders, and connecting rods for the pistons of the engine cylinders and the piston of the pump connected to a common crank pin, the timing of the valves and ignition of the internal combustion engines being so coordinated relative to the effective compression strokes of the air compressor that the power stroke of each piston of the engine will take place simultaneously with the effective compression strokes of the air compressor piston.

2. An air compressor, comprising a single pump cylinder, a pair of cylinders of an internal combustion engine adapted for alternate firing, pistons in the pump and engine cylinders, and connecting rods for said engine and pump pistons connected to a common crank pin, the connecting rods of the engine located at opposite sides of the pump connecting rod, the effective compression strokes of the air compressor piston taking place simultaneously with the effective power strokes of each engine piston.

CHARLES BELMONT SEGNER.
